STEPHEN V. MÜLLER, OF DETROIT, MICHIGAN

AEROPLANE-WING ARRANGEMENT

Application filed September 16, 1929. Serial No. 392,891.

This invention relates to improvements in aeroplane wing arrangements, and refers more particularly to an arrangement wherein each wing is divided into a plurality of transversely extending sections, and wherein means are provided for imparting a substantially vertical, or flapping, movement to the intermediate wing sections so that an aeroplane may ascend or descend more nearly vertically than with the usual type of fixed wings.

Another object of the invention is to provide means for turning the movable wing sections through substantially ninety degrees at the end of each vertical movement, so that as they rise they lie in a substantially vertical position, and as they move downwards they lie substantially horizontally.

A further object of the invention is to provide means for moving the end wing sections away from the intermediate movable sections before the commencement of movement of the latter thereby affording ample clearance, and also for returning the end wing sections so that they overlap portions of the adjacent intermediate sections when movement of the latter is no longer required, as for instance when it is desired to use the aeroplane in the normal manner for flying.

Yet another object of the invention is to provide means for turning one intermediate wing section on each side into vertical position as the end sections are moved outwards, and for returning that intermediate section on each side back to its horizontal position as the end sections are moved back towards one another to form continuous wings after the flapping movement has stopped.

With these and other objects and advantages in view which will become apparent as the specification proceeds, the invention is illustrated in the accompanying drawings in which

Figure 1 illustrates a side elevation of an aeroplane to which the invention is applied.

Figure 2 is a longitudinal section on the line 2—2 of Figure 3 showing the wing moving mechanism.

Figure 3 is a partial plan view of the wing moving mechanism.

Figure 4 is a section on the line 4—4 of Figure 3, and

Figures 5 and 6 are details.

Referring to the drawings, 1 designates an aeroplane having wings 2 on both sides. 55 Each wing consists of a plurality of sections 2^a, 2^b, 2^c and 2^d; and the adjacent margins of these sections are so formed as to overlap one another when they are in their normal flying position shown in Figure 1. 60 The wing sections 2^a and 2^d are continuous and extend right across the aeroplane, whereas the intermediate wing sections 2^b and 2^c are separate on opposite sides of the machine.

Suitably supported on the fuselage 3 are 65 longitudinal guides 4 integral with which, along their undersides, are inturned channels 4^a. An axle 5 extends between the guides 4 and has its extremities supported by the latter. Slidable longitudinally in the channels 70 4^a are racks 6, and fixed on the axle 5 are partial gears 7 each of which meshes with one of the said racks. Fixed on the axle 5 is an arm 8 to the other end of which a rod 9 is 75 pivotally secured. The opposite end of this rod is connected to a bell crank 10 so that by movement of a handle 10^a integral with the latter the axle 5 and partial gears 7 are turned. The racks 6 are connected to the front wing section 2^a by means of members 11 80 so that movement of the racks causes the front wing section to move longitudinally of the machine. 2^{aa} indicates the position of the front wing section when it has been moved forward from its adjacent wing sections 2^b. 85

Connected to the racks 6 by connecting rods 12 are partial gears 14 rotatable on the guides 4; these partial gears are adapted to mesh with gears 15 fixed on the shafts or supporting members 16 for the wing sections 2^c, so that as the wing section 2^a is moved outwards into the position indicated at 2^{aa} the wing sections 2^c are turned into the vertical position shown in Figures 2, 3 and 4. Other connecting rods 17 extend from the 95 partial gears 14 to arms 18 pivotal on projections 4^b integral with the rear ends of the guides 4. To the outer ends of these arms 18 the rear wing section 2^d is pivotally secured. Then as the wing section 2^a is 100

5 moved forward into its position 2^{aa}, and the wing sections 2^c are turned so as to assume a substantially vertical position, the rear wing section 2^d is also moved into its position 2^{ad}. The intermediate wing sections are then ready to be moved up and down.

10 Between the guides 4 are supports 19 mounted on the fuselage 3 and having bearings 20 therein for a crank shaft 21, the extremity 21^a of which is provided with any desired form of driving means—not shown. Mounted between the frames 19 are cylinders 22 in which plungers 23 are reciprocated by connecting rods 24 mounted on the said crank shaft 21. Each plunger 23 has a pair of opposed sockets 25 in its sides to carry balls 26 through which the inner extremities of supporting members 27 and 16 extend. These supporting members 27 and 20 16 carry the wing sections 2^b and 2^c respectively.

15 On one end of the crank shaft 21 a partial gear 28 is secured which alternately with two gears 29 and 30 both of which are fixed on a vertical spindle 31, so that rotation is imparted to the latter first in one direction and then in the other. Moreover rotation of the spindle 31 occurs in one direction or the other at each half revolution of the crank shaft 21. On the upper end of the spindle 31 is a spur gear 32 which meshes with a similar idler gear 33 and also with a rack 34 secured to the underside of a cross member 35. To the underside of the latter a second 25 rack 36 is also secured with which the idler gear 33 meshes. By this arrangement of double drive I am assured that the said cross member will remain in alignment as movement longitudinally of the aeroplane is imparted to it first in one direction and then in the other.

20 Above the cross member 35 is a second cross member 37, and means hereinafter described are employed at certain times for holding these cross members so that they move together. The member 35 is connected by extensions 38 to racks 39 which mesh with gears 40 fixed around the wing section supporting members 27, and the cross member 37 is connected by extensions 41 to racks 42 which mesh with the gears 15 fixed around the wing supporting members 16. Moreover the racks 39 are slideable in the guide channels 4^a. As the cross members 35 and 37 are moved longitudinally of the aeroplane in one direction or the other the wing sections 2^b are moved from a substantially vertical to a substantially horizontal position, or vice versa, and the wing sections 2^c are moved from a substantially horizontal position to a substantially vertical one, or vice versa. Moreover these turning movements are imparted to the wing sections as they 45 reach their top and bottom positions so that

they lie flat on their downward travel and on edge during their upward travel.

When rotation of the crank shaft 21 ceases, and the said shaft has been stopped in the position shown in Figures 2, 3 and 4 by means hereinafter described, the outer wing sections 2^c and 2^d are moved towards one another by movement of the handle 10^a. It will be noted that locking pins 45 adapted to extend through openings 35^a and 37^a in the cross members 35 and 37 hold both the latter so that they move together; these locking pins are pivotal on bell cranks 46. One arm 46^a of each of the latter has one end of a spring 47 secured to it, and the opposite ends of these springs are fastened to projections 48 integral with the cross member 35. The springs tend to hold the pins 45 in such position that they project through both openings 35^a and 37^a. However when the wing section 2^d is moved partly inwards towards the wing sections 2^c stops 49 on the connecting rods 17 engage the bell crank arms 46^a and withdraw the pins 45 from the openings 37^a. Then as movement of the connecting rods 17 is continued and the partial gears 14 continue to turn they mesh with the gears 15 so that the wing sections 2^c are turned from their substantially vertical to their substantially horizontal positions.

25 In order to insure the wing movement of the intermediate sections stopping when the crank shaft 21 is in the position shown in Figure 2 I provide a worm cam 50 on the said shaft. Depending from one of the supports 19 and pivotal thereon is a holder 51 having projections 52 with bearing slots 52^a therethrough for the passage of a member 53, the lower end 53^a of which is offset. Around the member 53 and between the projections 52 a spring 54 is arranged which tends to hold the member in the position shown in Figure 2. Projecting from the holder 51 is an arm 55 which is engaged by a pin 56 extending from the rod 9 when the latter is moved downwards to return the wing sections 2^a and 2^d towards one another. Downward movement of the rod 9 forces the offset end 53^a of the member 53 into engagement with the worm cam 50. The tension of the spring 54 acts as a brake and causes the crank shaft to stop when the said offset end reaches the position 53^{aa} shown in Figure 6.

30 60 denotes braces for the intermediate wing sections. At one end these braces are pivotally mounted on the connecting rod pins 24^a and their opposite ends each encircle one of the supporting members 27 or 16 which extend centrally of the said sections.

35 From the foregoing it is believed that the operation of the wing structure will be readily understood. Briefly it is as follows: For normal flying the wing sections are so arranged that they form two continuous and normal wings as shown in Figure 1. In

order to make more acute ascents or descents the wing sections 2^a and 2^d are moved outwardly and the intermediate wing sections 2^b and 2^c are flapped. To accomplish this the bell crank 10 is so moved that the outer wing sections 2^a and 2^d move outwardly and the wing sections 2^c are turned into their "on edge" position. Before the wing section 2^a has reached its outward position 2^{aa} the locking pins 45 enter the openings 35^a and 37^a so that the cross member 37 must move with the cross member 35. The crank shaft 21 is then turned so that the intermediate wing sections 2^b and 2^c are moved up and down, and through the vertical spindle 31 and cross members 35 and 37 these sections are turned through substantially ninety degrees at the ends of their strokes, so that they move downwards "on their flats" and upwards "on edge".

While in the foregoing the preferred embodiment of the invention has been described and shown it is understood that the construction is susceptible to such alterations and modifications as fall within the scope of the appended claims.

What I claim as my invention and desire to secure by Letters Patent is:

1. In an aeroplane wing arrangement, the combination of an aeroplane, a plurality of transverse wing sections thereon, all the sections on each side being adapted to lie contiguous to one another, means for moving the end wing sections longitudinally of the aeroplane, and means for flapping the intermediate wing sections.

2. In an aeroplane wing arrangement, the combination of an aeroplane, a plurality of transverse wing sections thereon, all the sections on each side being adapted to rest so that their margins extend over the margins of the adjacent sections, means for moving the end sections longitudinally of the aeroplane, and means for flapping the intermediate wing sections so that each opposed pair move in unison.

3. In an aeroplane wing arrangement, the combination of an aeroplane, a plurality of transverse wing sections thereon, the end sections being continuous completely across the aeroplane and the intermediate wing sections being separate on opposite sides of the aeroplane, means for moving the end sections longitudinally of the aeroplane, and means for flapping the intermediate sections.

4. In an aeroplane wing arrangement, the combination of an aeroplane, a plurality of transverse wing sections thereon, all the sections on each side being adapted to lie contiguous to one another, means for moving the end sections longitudinally, means for flapping the intermediate wing sections, and means for turning the latter so that they move upwardly "on edge" and downwardly "on their flats."

5. In an aeroplane wing arrangement, the combination of an aeroplane, a plurality of transverse wing sections thereon, the end sections being continuous completely across the aeroplane and the intermediate sections being separate on opposite sides thereof, means for flapping the intermediate wing sections, and means for turning the latter so that they move upwardly "on edge" and downwardly "on their flats."

6. In an aeroplane wing arrangement, the combination of an aeroplane, a plurality of transverse wing sections thereon, all the sections on each side being adapted to rest so that their margins extend over the margins of the adjacent sections, means for flapping the intermediate wing sections so that each opposed pair move in unison, and means for turning the intermediate wing sections so that they swing upwardly "on edge" and downwardly "on their flats."

7. In an aeroplane wing arrangement, the combination of an aeroplane, a plurality of wing sections extending outwardly on both sides, the end wing sections being continuous completely across the aeroplane and the intermediate wing sections being separate on opposite sides thereof, means for moving said end sections longitudinally, and means for turning one opposed pair of intermediate sections through substantially ninety degrees as said end sections are moved.

8. In an aeroplane wing arrangement, the combination of an aeroplane having a fuselage, guides longitudinally thereon, a rack movable on each of said guides, a transverse shaft extending between and supported by said guides, means for turning said shaft, gears on said shaft adapted to move said racks, a plurality of transverse wing sections extending outwardly beyond said guides, and one wing section extending completely across said aeroplane and so connected to said racks that it is moved longitudinally by the rotation of said shaft.

9. In an aeroplane wing arrangement, the combination of an aeroplane having a fuselage, guides longitudinally thereon, a rack movable on each of said guides, a transverse shaft extending between and supported by said guides, means for turning said shaft, gears on said shaft adapted to move said racks, and a plurality of transverse wing sections extending outwardly beyond said guides, both end wing sections extending completely across said aeroplane, one end section being connected to said racks and the other end wing section being connected to said gears so that rotation of said shaft moves both end wing sections simultaneously in opposite directions.

10. In an aeroplane wing arrangement, the combination of an aeroplane having a fuselage, longitudinal guides thereon, a shaft extending between said guides, means

for turning said shaft, a plurality of transverse wing sections on said aeroplane, the end sections extending completely across said aeroplane and the intermediate sections being separate on opposite sides, gears on said shaft, means for moving one end wing section when said shaft is turned, partial gears rotatable on said frame, connecting rods connecting said gears with partial gears so that they all turn together, said partial gears being adapted to turn one opposed pair of intermediate wing sections through substantially ninety degrees, and means for moving the other end wing section when said partial gears are turned.

11. In an aeroplane, the combination of an aeroplane having a fuselage, frames in said fuselage, a crank shaft supported by said frames, cylinders mounted between said frames, plungers in said cylinders adapted to be reciprocated by the movement of said crank shaft, a plurality of opposed wing sections extending laterally beyond said fuselage, supporting members secured to said wing sections pivotal on said fuselage, and the inner ends of said members terminating in said plungers so that as the latter are reciprocated the wing sections are flapped.

12. In an aeroplane wing arrangement, the combination of an aeroplane having a fuselage, frames in said fuselage, a crank shaft supported by said frames, cylinders mounted between said frames, plungers in said cylinders adapted to be reciprocated by the movement of said crank shaft, a plurality of opposed wing sections extending laterally beyond said fuselage, supporting members secured to said wing sections pivotal on said fuselage, the inner ends of said members terminating in said plungers so that as the latter are reciprocated the wing sections are flapped, and means operated by the rotation of said crank shaft for turning said wing sections through substantially ninety degrees when they reach their top and bottom positions.

13. In an aeroplane wing arrangement, the combination as described in claim 11 wherein brace rods are provided which are movable with the plungers and reinforce the wing sections throughout their movement.

14. In an aeroplane wing arrangement, the combination of an aeroplane having a fuselage, frames in said fuselage, a crank shaft supported by said frames, cylinders mounted between said frames, plungers in said cylinders adapted to be reciprocated by said crank shaft, a plurality of opposed wing sections extending laterally beyond said fuselage, the end wing sections being continuous completely across said aeroplane and the intermediate wing sections being separate on opposite sides thereof, and supporting members secured to said intermediate wing sections pivotal on said fuselage, the inner ends of said members termi-

nating in said plungers so that as the latter are reciprocated the intermediate wing sections are flapped.

15. In an aeroplane wing arrangement, the combination of an aeroplane having a fuselage, frames therein, a crank shaft supported by said frames, cylinders mounted between said frames, plungers in said cylinders adapted to be reciprocated by said crank shaft, a plurality of opposed wing sections, a plurality of opposed wing sections extending laterally beyond said fuselage, supporting members secured to said wing sections pivotal on said fuselage, the inner ends of said members terminating in said plungers so that as the latter are reciprocated the wing sections are flapped, a vertical spindle mounted in said fuselage, a partial gear on said crank shaft, gears on said spindle with each of which in turn said partial gear meshes so that said spindle is rotated first in one direction and then in the other and means for turning said wing sections through substantially ninety degrees each time said spindle is turned.

16. In an aeroplane wing arrangement as described in claim 15 the combination wherein as one opposed pair of wings are turned in one direction the other opposed pair of wings are turned in the opposite direction.

17. In an aeroplane wing arrangement as described in claim 11, the combination wherein means are provided for stopping the rotation of the crank shaft when the wing sections are in predetermined positions.

18. In an aeroplane wing arrangement, the combination of an aeroplane having a fuselage, frames in said fuselage, a crank shaft supported by said frames, cylinders mounted between said frames, plungers in said cylinders adapted to be reciprocated by said crank shaft, a plurality of opposed wing sections extending laterally beyond said fuselage, supporting members secured to said wing sections pivotal on said fuselage, the inner ends of said supporting members extending through said plungers so that as the latter are reciprocated the wing sections are flapped, a vertical spindle mounted on one of said frames, a partial gear on said crank shaft, gears on said spindle with each of which said partial gear meshes in turn so that said spindle is first turned in one direction and then in the other, cross members transversely of said fuselage adapted to move together in opposite directions according to the direction of rotation of said spindle and to be moved by the latter, gears on said wing supporting members, and racks connected to said cross members adapted to mesh with said supporting member gears so that movement of said cross members causes said wing sections to turn.

STEPHEN V. MÜLLER.
